UNITED STATES PATENT OFFICE.

HAROLD WILLIAM EDEN, OF CHICAGO, ILLINOIS, ASSIGNOR TO ALBAUGH-DOVER COMPANY, A CORPORATION OF ILLINOIS.

WASHING-MACHINE TUB.

Application filed January 12, 1920. Serial No. 350,957.

To all whom it may concern:

Be it known that I, HAROLD WILLIAM EDEN, a citizen of the United States, and a resident of the city of Chicago, in the 5 county of Cook and State of Illinois, have invented certain new and useful Improvements in a Washing-Machine Tub; and I do hereby declare that the following is a full, 10 clear, and exact description of the same, reference being had to the accompanying drawings, and to the numerals of reference marked thereon, which form a part of this specification.

This invention relates more particularly 15 to an improved form of a rotatable type of a washing machine tub, having a perforated radially disposed partition therein to divide the tub into clothes chambers.

It is an object of this invention to provide 20 an improved type of a washing machine tub.

Another object of the invention is to provide 25 a washing machine tub with a perforated radial vane in the lower portion thereof.

It is a further object of the invention to construct 30 a rotatable type of a washing machine tub with a partition permitting the water to flow from one side of the tub to the other during a washing operation to cause cleansing of clothes in the compartments formed by said partition.

It is an important object of this invention to construct 35 a cylindrical type of a partitioned washing machine tub, provided with a drain valve adapted to drain the clothes compartments of said tub.

Other and further important objects of 40 this invention will be apparent from the disclosures in the drawings and specification.

The invention (in a preferred form) is illustrated in the drawings and hereinafter more fully described.

On the drawings—
45 Figure 1 is an elevation of a washing machine partly broken away and equipped with an improved type of tub embodying the principles of this invention.

Figure 2 is an end view of the tub.
50 Figure 3 is a section taken on line 3—3 of Figure 2.

Figure 4 is a section taken on line 4—4 of Figure 3.

Figure 5 is an enlarged section of the 55 tub drain valve.

As shown on the drawings—

The reference numeral 1 indicates a washing machine supporting frame on which is mounted a wringer 2, a mechanism 3 for operating the wringer, and a driving motor 4. 60 Also connected to be driven by the motor 4 is a tub operating mechanism 5, adapted to partially rotate an improved type of a cylindrical tub.

The tub comprises a cylindrical wall 6 65 provided with an opening in the upper portion, which is adapted to be closed by means of a removable cover or door 7. The ends of the tub are closed by means of end walls 8 and 9 which are rigidly secured to the 70 cylindrical wall 6. Projecting axially through the tub is a shaft or axle 10 the ends 11 and 12 of which project through and are rigidly secured to plates 13, secured centrally on the tub end walls 8 and 9. The 75 shaft end 11 is journaled in the frame 1. The shaft end 12 is shaped to form a lug or key which is engaged with the tub operating mechanism 5 so that the tub may be partially rotated when the motor 4 operates the operating mechanism 5.

Secured on the shaft 10 is a partition or vane 14 having a plurality of apertures or openings 15 therein. The partition is disposed longitudinally in the lower half of the 85 tub in a radial position with the ends of the partition rigidly secured to the tub end walls 8 and 9. The lower edge of the partition 14 is spaced above the bottom portion of the tub to afford an opening or slot 16 90 below the partition. The partition 14 serves to divide the lower half of the tub into two clothes compartments or chambers.

Secured in the bottom of the tub near the end wall 8 is a drain elbow 17 on the end 95 of which is mounted a passaged valve casing 18 having a hollow plug valve 19 rotatably seated therein. The valve 19 is provided with an outlet opening 20. Formed on top of the valve 19 is an apertured lug 21 having 100 one end of a valve rod 22 engaged therethrough. The valve rod extends across the end wall 8 and is rotatably held in place by a bracket 23. The upper end of the valve rod is bent to afford a handle 24 to 105 facilitate turning of the rod to cause adjustment of the valve 19.

The operation is as follows—

Water is admitted into the tub through the door opening, and fills the clothes com- 110

parts. Clothes to be washed are placed in both of the compartments provided on opposite sides of the perforated partition plate 14. When the water and clothes are 5 in the tub, the cover 7 is closed, and the motor 4 is started. The motor drives the operating mechanism 5, which acts to alternately rock or partially rotate the tub shaft 10, thereby causing the tub to partially rotate. Partial rotation of the tub causes the water therein to alternately flow from one clothes compartment to the other through the partition openings 15 and through the slot 16 below the partition. 10 The agitated water washes through the clothes and thereby cleans them.

When the clothes have been thoroughly cleaned they are removed from the tubs and the sediment and water are drained from 15 the tub by turning the rod 22, until the valve 19 is set with the valve opening 20 registering with the passage in the elbow 17. The space 16 below the partition 14 permits dirt and sediment from both of the 25 clothes compartments to collect in the bottom of the tub and be drained off through the drain elbow 17 when the valve 19 is open.

I am aware that numerous details of construction may be varied through a wide 30 range without departing from the principles of this invention, and I therefore do not purpose limiting the patent granted otherwise than necessitated by the prior art.

I claim as my invention: 35

In a washing machine, an imperforate oscillatable suds and clothes cylinder provided with an operating shaft at its central axis, a perforated partition secured to said shaft and extending therefrom to within 40 a short distance from the lower cylindrical wall of said casing to divide the lower half of said cylinder into two compartments with a sediment passage therebetween, and a drain cock extending through the lower 45 cylindrical wall of said cylinder in the plane of said partition to receive sediments from both compartments.

In testimony whereof I have hereunto subscribed my name in the presence of two 50 subscribing witnesses.

HAROLD WILLIAM EDEN.
